UNITED STATES PATENT OFFICE.

GEORGE W. LENTZ, OF CANTON, OHIO, ASSIGNOR, BY MESNE ASSIGNMENTS, TO THE BERGER MANUFACTURING COMPANY, OF CANTON, OHIO, A CORPORATION OF OHIO.

SHEET-STACKING MACHINE.

Application filed February 6, 1926. Serial No. 86,610.

The invention relates to machines for stacking sheets delivered from a rolling mill and the like and more particularly for stacking highly finished sheets delivered from 5 highly polished cold finishing rolls, in such a manner that the sheets are automatically stacked one directly upon the other without sliding and shifting them on each other and thus preventing any marring or scratching of 10 their surfaces. Such sheets have heretofore been stacked by the use of a number of laborers, who catch the sheets as they issue from the finishing rolls and stack them in a pack.

The object of the invention is to provide 15 an automatic sheet stacking machine for continuous operation in rear of a sheet finishing mill or the like, so as to eliminate the use of manual labor which has heretofore been required for that purpose; and to provide 20 mechanism which will stack sheets with less damage than is ordinarily done by manual labor.

These and ancillary objects are attained by 25 the mechanism of the present improvement, which may be described in a general way as including retractible sheet catching and conveying means operative to catch and convey the sheets at the edges thereof, and means for automatically retracting said catching 30 and conveying means and dropping sheets caught and conveyed thereby to make a stack.

A preferred embodiment of the invention is illustrated and described in the accompanying drawings forming part hereof, in 35 which—

Figure 1 is a plan view of an improved sheet stacking machine in operative combination with a sheet finishing mill shown partially in cross section, and a sheet delivery table; 40 Fig. 2, a vertical cross section of the same as on line 2—2, Fig. 1;

Fig. 3, an end elevation of the sheet stacking machine looking in the direction of arrows 3—3, Fig. 1;

Fig. 4, an enlarged fragmentary end elevation looking in the same direction as in Fig. 3, illustrating a catcher and conveyor wheel and mounting, and retracting means therefor; and

Fig. 5, an enlarged fragmentary side elevation of the stacking machine, illustrating a catcher and conveyor wheel and mounting, and retracting means therefor.

Similar numerals refer to similar parts throughout the drawings.

The sheet stacking machine indicated generally at 1 receives sheets delivered to it, as by a sheet finishing mill indicated generally at 2 of well known design, and may include highly polished power rotated finishing rolls 3 and 3' through which sheets are fed in a well known manner from a feed table 4. The finishing mill 2 is provided upon its delivery side 5 with sheet guide and supporting wheels or rolls 6 and 6' having relatively deep V- 60 peripheral grooves 7 therein for guiding the side edges 8 and 8' of a sheet 9 being delivered from the mill. The plane of the peripheral V-grooves of the wheel are horizontal, and the grooves of all the wheels 6 and 6' are 65 preferably in the same plane for guiding and supporting a sheet therethrough without bending the same.

The pair of guide wheels 6 for guiding and supporting the edge 8 of a sheet 9 are mounted upon vertical spindles 10 supported on the ends of a spacer bar 11; the other pair of groove wheels 6' for guiding and supporting the edge 8' of sheet 9, are likewise mounted upon vertical spindles 10 supported at the 80 ends of a spacer bar 11'. Spacer bars 11 and 11' are preferably straight and parallel with each other and have longitudinal axes parallel with the line of motion of the sheets through the mill.

The bar 11 is provided with a plurality of cylindric apertures 12 having internal threads which may be right hand while the bar 11' is provided with a plurality of apertures 12' having internal threads which may 90 be left hand and whose axes are aligned with the axes of the apertures 12, all of the aperture axes being at right angles to the longitudinal axes of the bars 11 and 11' for receiving parallel shafts 13 provided with right hand threaded ends 13' for screwing into the right hand internally threaded apertures 12 and with lefthand threaded ends 13'' for screwing into the left hand threaded apertures 11 in the bars 11'. The ends 13' are supported 100 as by spaced bearings 14 secured to one side frame and bearing block 15 of the finishing mill 2; while the ends 13'' are supported as by bearings 14' secured to the other side frame and bearing block 15' of the mill 2. 105 Below the bearings 14' upon the frame 15'

a worm shaft 16 extending at right angles to the shafts 13 is rotatably mounted and provided at its outer extreme end with an operating hand wheel 17 and at intermediate points upon its length with worm gears 18 keyed thereto and meshing with worm wheels 19 keyed to the shafts 13. A rotation of the hand wheel 17, through the above described worm and wheel gearing, will consequently 10 vary the spacing of the aligned guide and supporting wheels 6 from the aligned guide and supporting wheels 6' to accommodate sheets of varying widths.

The top of the feed table 4, the nip 3" of the 15 rolls 3 and 3' through which the sheets are rolled, and the mutual plane of the V-apexes of the rolls 6 and 6' are intended to be in the same plane and at the same level; and the function of the aligned wheels 6 spaced from 20 the aligned wheels 6' is to support and guide sheets issuing from the mill 2 into the sheet stacking machine 1.

The sheet stacking machine indicated generally at 1 includes one set of aligned sheet 25 guide and supporting wheels 6^a provided with V-grooves 7^a having their apexes in the same plane, and with another set of aligned sheet guide and supporting wheels 6'^a spaced from and parallel with the first set, 30 and provided with peripheral V-grooves 7^a' in the same plane and in the plane of the grooves 7^a, both sets of grooves being normally in the common level plane in which are located the top of the feed table 4, the nip 3" 35 of the rolls, and the V-grooves of the wheels 6 and 6' as heretofore described. The V-grooves 7^a and 7^a' of the wheels 6^a and 6'^a are adapted to catch highly polished sheets issuing from the mill 2 at the edges thereof, 40 and to convey the same without bending them.

The parallel aligned sets of wheels 6^a and 6'^a with other parts about to be described constitute retractable sheet catching, conveying and stacking means.

45 Each wheel 6^a and 6'^a is secured at the upper end of, and driven by a normally vertical shaft 20, journaled in a normally vertical journal aperture 21' of a bearing bracket 21 and supported thereon, as by a collar 22, 50 the shaft having a bevel gear 23 keyed thereto at its lower end. Each bearing bracket 21 is also provided with spaced bearing feet 21^a having aligned apertures 21" at right angles to the aperture 21'.

55 The bearing brackets for the wheels 6^a are all pivotally mounted upon a horizontal shaft 24, extending through the apertures 21" of the bearing feet 21^a and having keyed thereto a plurality of bevel gears 25, each of which is 60 in mesh with one of the bevel gears 23.

The bearing brackets for the wheels 6'^a are likewise pivotally mounted upon a horizontal shaft 24' extending through the apertures 21" of the bearing feet 21^a, and having keyed 65 thereto a plurality of bevel gears 25, each of

which is in mesh with one of the bevel gears 23.

Bracket bearing blocks 26 are spaced between the bearing feet 21^a and provided with apertures 26' in alignment with the apertures 21", and through all of which apertures the shafts 24 and 24' extend. The blocks 26 are secured as by bolts 27 to supporting channels 28 and 28' extending in the direction of the aligned wheels 6^a and 6'^a, and the channels are themselves slidably mounted upon a plurality of transversely extending parallel shafts 29, said shafts being supported upon the foundation F by means of bearing blocks 30.

For varying the transverse spacing of the sets of aligned rolls 6^a and 6'^a, the channels 28 and 28' upon which the rolls are mounted as aforesaid, are provided respectively with pairs of depending apertured blocks 30' and 30".

The apertures in the blocks 30' are provided with internal right hand threads, while the apertures in the blocks 30" are provided with left hand threads, and the blocks 30' and 30" are oppositely mounted upon the channels 28 and 28' so that their internally threaded apertures are aligned with each other to receive shafts 31 which are journaled at their middles in bearing blocks 32 secured to a foundation channel 33, each shaft 31 being provided at one end with right hand threads 31' screwed into a right hand threaded block 30' and at the other end with left hand threads 31" screwed into the left hand threaded block 30".

Each shaft 31 may be journaled at one end in a bearing block 32' secured to foundation channel 33', and the shafts may be provided with thrust collars 31^a operating against the bearing blocks 32'. At their other ends the shafts 31 may be journaled in bearing blocks 32" secured to foundation channel 33", and the shafts may extend through the bearing blocks 32" and be provided at their extended ends with bevel gears 34 keyed thereon.

The bevel gears 34 are meshed with bevel gears 34' spaced and keyed upon a shaft 35 angular to the shafts 31, and likewise journaled in the bearing blocks 32", and having 115 keyed thereto at one end a bevel gear 36 in mesh with a bevel gear 36^a mounted at the bottom of a vertically supported shaft 37 provided at its upper end with a hand wheel 38, the shaft 37 being journaled in a vertical bracket 39.

A rotation of the hand wheel 38 will, therefore, through the bevel gearing just described and the right and left hand threaded shafts 31, consequently vary the spacing of the aligned sheet conveying and stacking wheels 6^a and 6'^a to accommodate sheets of varying widths.

Shafts 24 and 24' are each provided at one of their ends respectively with bevel gears 40

and 40' in mesh respectively with bevel gears 41 and 41' keyed upon a shaft 42 journaled in suitable bearing blocks 43, 43' and 43''.

The bevel gears 41 and 41' are keyed upon the shaft 42 for sliding lengthwise thereon, upon varying the spacing of the aligned sets of wheels 6^a and 6^{a'}, as heretofore described.

Shaft 42 is connected at an outside end 42^a as by gearing 44 with a motor 45 for causing the conveyor wheels 6^a and 6^{a'} to rotate and convey sheets delivered thereto from the mill 2 away from said mill and in position for automatic stacking.

For providing automatic retracting means for the wheels 6^a and 6^{a'}, angle irons 46 and 46' are secured to the upper ends of the bearing brackets 21 for the shafts for the respective sets of wheels 6^a and 6^{a'}.

The bearing blocks 26^a are provided between centrally located brackets 21 and each block 26^a is pivotally connected as at 47 with an upward extending link 48 having a solenoid 49 mounted at its upper end, the longitudinal axis of each solenoid being at an angle 25 with the longitudinal axis of the link 48.

A piston 50 is slidably mounted in the aperture 49^a of each solenoid, and pivotally connected as at 51 with relatively short parallel links 52 which are likewise pivotally connected as at 53 to pivot blocks 52, two of which are secured to and depend from each of the angle irons 46 and 46'.

For limiting the inward pivotal movement of the link 48 to provide for a normally vertical positioning of the brackets 21, the links 48 are provided near their pivotal connections 47 with projecting lugs 55 abutting against the outside faces 26^{a'} of the blocks 26^a.

Pivot lugs 56 extend upward from the blocks 26^a and are provided with hooks 57 pivotally mounted thereon as at 58 for cooperation with pins 59 mounted upon the links 48. The hooks 57 are normally in hooked position over the pins 59 for maintaining the links 48 in the upwardly extending position illustrated in Fig. 3.

Each piston 50 extends a substantial distance into its solenoid aperture 49^a and is pin connected to a cylindric rod 60 extending through and beyond the aperture and upon which a compression spring 61 is positioned abutting at its inner end with the end of the piston 50 and at its outer end with an adjustable rod guide and spring stop 62 screw mounted in a projecting cylindric extension 63 of the solenoid spool 49^b.

The rod 60 is threaded at its extreme outer end 60' and provided with adjusting nuts 64, the rod freely sliding through the stop 62 so that one of the nuts 64 may abut against said stop and provide adjustment for positioning the bracket 21 and a stop for inward movements of the piston 50.

The solenoid winding, indicated by 49^c of

each solenoid 49, is provided with lead wires 65 and 65', and one wire 65 of one solenoid may be connected to one power line wire 66 while the lead wire 65' of the other solenoid may be connected with the other power line 70 wire 66'.

For providing automatic switching control for the solenoids, the wire 65 of the second mentioned solenoid having its wire 65' connected to wire 66', may be connected as by 75 wire 67 with contact 68 of the automatic pivotal switch 70; while the wire 65' of the first mentioned solenoid having its wire 65 connected with power line wire 66, may be connected as by wire 67' with the other contact 80 69 of the switch 70.

The switch 70 includes blades 71 and 72 pivotally connected with each other as at 73, the contact 68 being mounted upon and insulated from the blade 71 and the contact 85 69 being mounted upon and insulated from the blade 72. Blade 71 is secured to a horizontally extending bracket 74, having an angular extension 75 removably secured to the angle 46' as by clamp 76.

The bracket 74 is mounted near the extreme end of the angle 46' so that the switch 70 depends therefrom in the line of motion of sheets delivered from the mill and conveyed through the wheels 6^a and 6^{a'}.

The blade 72 of the switch 70 is provided with a downwardly extending lever arm 77 which may be impinged by a sheet conveyed through the wheels 6^a and 6^{a'} to close the solenoid circuit heretofore described.

The peripheral velocity of the driven rolls 3 and 3' is preferably less than the peripheral velocity of the driven wheels 6^a and 6^{a'}. The wheels 6 and 6' are idler wheels freely rotatable upon their spindles 10.

In operation the sheet is fed from the feed table 4 through the finishing rolls 3 and 3' and the end of the sheet issuing from the rolls passes through the idler guide wheels 6 and 6' and the side edges of the sheet are immediately caught in the rotating V grooves 7^a and 7^{a'} of the catcher and conveyor wheels 6^a and 6^{a'} having a greater peripheral velocity than the peripheral velocity of the rolls, and the sheet is conveyed thereby at the velocity of the rolls until the other end of the sheet clears the rolls, whereupon the linear velocity of the sheet is immediately increased to the peripheral velocity of the grooves 7^a and 7^{a'} of the conveyor rolls 6^a and 6^{a'}, so as speedily to clear the sheet from the mill to avoid interference with successive sheets fed therethrough.

The conveyor wheels 6^a and 6^{a'} convey the caught sheet in the direction of the arrow A until the outer end 9' of the sheet impinges the depending lever 77 of the switch 70, abutting the contacts 68 and 69 with each other, thus closing the solenoid circuit and energizing the solenoids, which are properly wound,

so that when energized they outwardly draw the pistons 50 against the reaction of the spring 61 to retract the wheels 6^a and 6^{a'} sufficiently to enable the sheet to drop directly 5 down upon blocks 78 positioned between the aligned wheels 6^a and 6^{a'}.

When the sheet drops, the center of gravity of the blade 72 of the switch is such that the switch contacts will separate, thus opening 10 the solenoid circuit and enabling springs 61 to reposition the shafts of the wheels 6^a and 6^{a'} in their normal vertical position ready to catch and convey and automatically stack the next sheet fed through the mill.

15 Referring to Fig. 4, an enlarged, fragmentary view of portions of the device, the dotted position P indicates the extreme lateral displacement of the wheels 6^{a'} when automatically actuated by the energized solenoids as 20 aforesaid.

After a stack of sheets indicated by S in Fig. 3 has been automatically stacked by the machine, hook 57 may be swung up about its pivotal mounting 58 to enable the wheels 6^{a'} 25 to be laterally displaced to the position indicated by P¹.

Wheels 6^a, obviously, by the operation of the machine, would be displaced to similar positions in the opposite direction.

30 The position of the wheels indicated by P¹ enables the stack of sheets S to be lifted directly up, as by a crane and removed from the machine. By reclamping the hooks 57 over the pins 59, the machine is ready for 35 further automatic operation.

I claim:

1. A sheet stacking machine including retractable wheels for catching and conveying a sheet at the edges thereof and means for re-40 tracting the catching and conveying wheels to drop a sheet caught thereby, and the sheet catching wheels including means for maintaining a caught sheet at a predetermined elevation until the caught sheet is dropped by retraction of the catching wheels.

2. A sheet stacking machine including retractable wheels for catching and conveying a sheet at the edges thereof, shafts upon 50 which the wheels are mounted, and means for retracting the wheels to drop a sheet caught thereby, and the sheet catching wheels including means for maintaining a caught sheet at a predetermined elevation until the caught sheet is dropped by retraction of the catching wheels.

3. A sheet stacking machine including wheels for catching and conveying a sheet at the edges thereof, means for rotating the wheels, and means for retracting the wheels 60 to drop a sheet caught thereby, and the sheet catching wheels including means for maintaining a caught sheet at a predetermined elevation until the caught sheet is dropped by retraction of the catching wheels.

65 4. A sheet stacking machine including

wheels for catching and conveying a sheet at the edges thereof, means for rotating the wheels, and means for automatically retracting the wheels to drop a sheet caught thereby, and the sheet catching wheels including 70 means for maintaining a caught sheet at a predetermined elevation until the caught sheet is dropped by retraction of the catching wheels.

5. A sheet stacking machine including 75 wheels for catching and conveying a sheet at the edges thereof, means for rotating the wheels, means for delivering a sheet to be caught by the wheels, and means for retracting the wheels to drop the sheet caught thereby, and the sheet catching wheels including 80 means for maintaining a caught sheet at a predetermined elevation until the caught sheet is dropped by retraction of the catching wheels.

6. A sheet stacking machine including sheet catching and conveying wheels, means for rotating the wheels, and means for delivering a sheet to the wheels, the peripheral velocity of the wheels being different from the 90 velocity of a delivered sheet, and the axes of rotation of the wheels being angular to the plane of the delivered sheet, and the sheet catching wheels including means for maintaining a caught sheet at a predetermined 95 elevation until the caught sheet is dropped by retraction of the catching wheels.

7. A sheet stacking machine including sheet catching and conveying wheels, means for rotating the wheels, and means for delivering a sheet to the wheels, the peripheral velocity of the wheels being greater than the 100 velocity of the delivered sheet, and the axes of rotation of the wheels being angular to the plane of the delivered sheet, and the sheet catching wheels including means for maintaining a caught sheet at a predetermined elevation until the caught sheet is dropped by retraction of the catching wheels.

8. A sheet stacking machine including sheet catching and conveying wheels, means for rotating the wheels, means for delivering a sheet to the wheels, the peripheral velocity of the wheels being different from the 110 velocity of a delivered sheet, and means for retracting the wheels to drop the sheet caught thereby.

9. A sheet stacking machine including sheet catching and conveying wheels, means for rotating the wheels, means for delivering a sheet to the wheels, the peripheral velocity of the wheels being greater than the 120 velocity of the delivered sheet, and means for retracting the wheels to drop the sheet caught thereby.

10. In combination, driven sheet rolls and retractable sheet catching and conveying wheels for catching sheets delivered from the rolls, and the axes of rotation of the 125 wheels being angular to the axes of rotation 130

of the rolls, and the sheet catching wheels including means for maintaining a caught sheet at a predetermined elevation until the caught sheet is dropped by retraction of the 5 catching wheels.

11. In combination, driven sheet rolls and retractable driven sheet catching and conveying wheels for catching sheets delivered from the rolls, and the axes of rotation of the 10 wheels being angular to the axes of rotation of the rolls, and the sheet catching wheels including means for maintaining a caught sheet at a predetermined elevation until the caught sheet is dropped by retraction 15 of the catching wheels.

12. In combination, driven sheet rolls and retractable driven sheet catching and conveying wheels for catching sheets delivered from the rolls, the peripheral velocity of the 20 wheels being different from the peripheral velocity of the rolls, and the axes of rotation of the wheels being angular to the axes of rotation of the rolls, and the sheet catching wheels including means for maintaining a 25 caught sheet at a predetermined elevation until the caught sheet is dropped by retraction of the catching wheels.

13. In combination, driven sheet rolls and retractable driven sheet catching and conveying 30 wheels for catching sheets delivered from the rolls, the peripheral velocity of the

wheels being greater than the peripheral velocity of the rolls, and the axes of rotation of the wheels being angular to the axes of rotation of the rolls, and the sheet catching 35 wheels including means for maintaining a caught sheet at a predetermined elevation until the caught sheet is dropped by retraction of the catching wheels.

14. A sheet stacking machine including 40 wheels for catching and conveying a sheet at the edges of the sheet, and means for moving the wheels towards and away from the edges of the sheet for alternately positioning the wheels for catching and dropping the 45 sheet.

15. A sheet stacking machine including a pair of laterally spaced longitudinally extending members, means on each member adapted for receiving and affording vertical 50 support to the lateral edges of a sheet as it is moved longitudinally between the members, and means actuated by the moving sheet when it attains a predetermined position with respect to the members and operative to move 55 the members simultaneously in opposite directions away from the edges of the sheet for withdrawing the support for the sheet and allowing it to fall vertically.

In testimony that I claim the above, I have hereunto subscribed my name.

GEORGE W. LENTZ.
